DISPLAY CASE FOR A PERFUME BOTTLE

Walter Langer, New York, N.Y., assignor to Evyan Perfumes, Inc., New York, N.Y., a corporation of New York

Filed June 17, 1959, Ser. No. 56,399

Term of patent 14 years

(Cl. D58—12.7)

FIG. 1 is a display case for a perfume bottle shown in open position, showing my new design;

FIG. 2 is a top plan view thereof shown in closed position;

FIG. 3 is a front elevational view thereof shown in closed position; and

FIG. 4 is a side elevational view thereof shown in closed position.

The rear and side not shown are the same as the respective front and side shown.

The broken line showing of the bottle is for illustrative purposes only.

I claim:

The ornamental design for a display case for a perfume bottle, substantially as shown and described.
